COMBINED CHAIR BACK AND SEAT

John D. Eves, Cortland, N.Y., and Robert Martin Engelbrecht, Rocky Hill, N.J., assignors to The Brewer-Titchener Corporation, Cortland, N.Y., a corporation of New York

Application January 13, 1958, Serial No. 49,220

Term of patent 14 years

(Cl. D15—1)

Fig. 1 is a front perspective view of a chair embodying our new combined chair back and seat design;

Fig. 2 is a front elevational view thereof;

Fig. 3 is a side elevational view thereof; and

Fig. 4 is a back elevational view thereof.

The dotted lines in the drawings are for illustrative purposes only.

We claim:

The ornamental design for a combined chair back and seat, as shown and described.
